CLAIM

The ornamental design for a wireless remote control for a boat interceptor trim tab, as shown and described.

DESCRIPTION

The patent or application file contains at least one drawing executed in color. Copies of this patent or patent application publication with color drawing(s) will be provided by the Office upon request and payment of the necessary fee.

1. Wireless remote control for a boat interceptor trim tab

1.1 : Front

1.2 : Back

1.3 : Perspective

1.4 : Right

1.5 : Left

1.6 : Top

1.7 : Bottom

The portions of the wireless remote control for a boat interceptor trim tab shown with purple overlay form no part of the claimed design.

1 Claim, 7 Drawing Sheets
